SINK

Jack N. Kaiser, Louisville, Ky., assignor to American Radiator & Standard Sanitary Corporation, New York, N.Y., a corporation of Delaware

Filed Oct. 23, 1965, Ser. No. 87,833

Term of patent 14 years

(Cl. D4—2)

FIG. 1 is a perspective view of a sink showing my new design;

FIG. 2 is a front elevational view thereof.

The dominant features of my design reside in the portions shown in full lines, and the faucet fixture shown in FIG. 2 is included for illustrative purposes only.

I claim:

The ornamental design for a sink, substantially as shown and described.
